(57) **CLAIM**

The ornamental design for a trash container, as shown and described.

DESCRIPTION

FIG. 1 is a perspective view of a trash container showing my new design;

FIG. 2 is another perspective view of the trash container;

FIG. 3 is a perspective view of the trash container where the trash container is in a configuration of use;

FIG. 4 is a front elevational view of the trash container shown in FIG. 1;

FIG. 5 is a rear elevational view of the trash container shown in FIG. 1;

FIG. 6 is a left side elevational view of the trash container shown in FIG. 1;

FIG. 7 is a right side elevational view of the trash container shown in FIG. 1;

FIG. 8 is a top plan view of the trash container shown in FIG. 1; and,

FIG. 9 is a bottom plan view of the trash container shown in FIG. 1.

The broken lines in the figures show portions of the trash container, which form no part of the claimed design.
